SPLIT ANODE FOR BENT GUN ION TRAP
CATHODE-RAY TUBES

Eric Pohle, Clifton, N. J., assignor to Allen B.
Du Mont Laboratories, Inc., Clifton, N. J., a
corporation of Delaware

Application June 6, 1950, Serial No. 166,401

7 Claims. (Cl. 313—83)

1

This invention relates to cathode ray tubes having a single magnet ion trap and more particularly to the anode tubes of this type.

In cathode ray tubes of the type described in copending application, Serial No. 129,260 by Kenneth Hoagland, assigned to applicant's assignee, one of the most expensive elements of the electron gun and the one which is most difficult to fabricate is the bent metallic portion of the anode. This bent portion of the anode comprises two cylindrical sections having the axes thereof joined at an angle. These bent anodes commonly are fabricated from seamless nickel tubing, which is cut to length, held in a vise and bent to the proper angle. It is difficult to bend this tubing without having it buckle, tear or spring back to a bend of smaller angle than is desired. After the bending, it is necessary to swage one end of the tubing to form a large radius corona shield at the end proximal to the location of the second grid. At the other end of the anode, close tolerances on the size of the limiting aperture cup must be held in order to get the cup to fit snugly into the end of the anode tubing. These several factors plus the initial cost of the seamless tubing, which is considerably more expensive than flat stock of the same thickness, combine to increase the cost of the complete bent anode structure.

Accordingly, one object of this invention is to provide an improved bent anode which avoids the enumerated difficulties by fabricating the structure from flat stock.

Other objects are to provide a cheaper bent anode or a bent anode which allows easy assembly with the rest of the electrodes making up the electron gun.

Other objects and advantages of the invention will be apparent after studying the following specification.

The invention, accordingly, is embodied in an electron gun structure including a bent anode fabricated from flat stock to give a structure formed of a plurality of sections; the sections being matched to form the tubular anode bent at the desired angle, and the invention is characterized by the features of construction, combinations of elements and arrangement of parts hereinafter to be described.

Referring to the drawings:

Figure 1 shows an electron gun comprising an anode constructed according to this invention;

Figure 2 shows a cross section of the anode in Figure 1;

2

Figure 3 shows a bottom view of the anode in Figure 1;

Figure 4 illustrates the method of fabricating the anode;

5 Figure 5 shows an electron gun utilizing an anode constructed according to this invention;

Figure 6 is another view of the electron gun in Figure 5; and

10 Figure 7 illustrates the method of making the metal support posts in Figures 5 and 6.

The electron gun shown in Figure 1 comprises a base stem 10, lead in wires 11, a grid structure 12, a cup shaped second grid 13, and a bent anode 14, all fastened in alignment to a pair of 15 insulating support rods 15. Only one rod appears in Figure 1, for they are in the same plane and parallel. The control grid 12 is clamped to the support rods 15 by a pair of semi-cylindrical straps 19 and 21 with radial ends for 20 matching them together and longitudinal fingers 22 and 23 extending therefrom. An insulating disc 24 which serves to carry the heater (not shown) is held in place by the fingers 22 and 23.

The second grid 13 has a rolled or turned edge 25 26 forming a corona shield and is held in place facing the anode 14 by a groove 27 in the side wall of the cup 12. A corona shield 28 similar to 26 is held in place in the anode 14 by a groove 29.

30 The anode 14 comprises a straight cylindrical fore part 31 angularly displaced from the cylindrical hind part 32, which is coaxially aligned with the control grid 12 and the second grid 13. For this preferred embodiment of the invention, anode 14 is pressed or drawn in two matching sections 33 and 34 (Figure 3), which are mirror images of each other and are preferably joined together by integrally joining the abutting pairs of flanges 36 and 37 along the 35 tops and bottoms thereof, respectively. To insure perfect matching of the two halves 33 and 34, they may be pressed or drawn adjacent to each other on a sheet of flat metal stock to take advantage of the local homogeneity of the metal.

40 45 A limiting aperture cup 38 is attached to the front end of the anode 14 by welding around the periphery thereof, or, alternatively, the cup 38 may be held in place by the stiffening rib 39. A pair of centering springs 41 and 42 are 45 snapped onto the outer edge of the cup 38 to hold the forward part of the gun in place in the cathode ray tube neck (not shown) and to make contact with the conductive coating (also not shown) commonly deposited on said neck.

50 55 The anode 14 is attached to the support rods 15 by strap 43 having a transverse stiffening rib 44,

a longitudinal rib 46 forming a backbone along the center of the strap, and a pair of C-shaped clamps 47 extending from the body of the strap 43. The strap 43 is integrally joined to the forward part 31 of the anode 13 and is located in the notch 49 with the rib 46 fitting over the bottom of the notch. This notch 49 assists in the longitudinal location of the strap 43 although the notch is preferably made sufficiently long to provide a slight allowance for its exact placement.

The fitting of the corona shield 28 in the rib 29 is shown more clearly in Figure 2 along with the positioning of the limiting aperture cup 38. The flange 37 is shown in Figure 2 with the notch extending only part way in to the semi-cylindrical portion 34. Notch 49 is not extended back to the cylinder because in cutting it out, by stamping, a slight feather edge is inevitably left which contributes to irregularity in the electric field in the anode.

The method of fabricating the anode is illustrated in Figure 4 where die 51 is shown holding the semi-cylindrical half section 34 in position for the punch 52 which will cut out the notch 49 from the flange 37. If the width of the punch 52 were extended laterally to cut the notch 49 all the way to the semi-cylindrical wall portion 34, it would be necessary to cut back the die 51 correspondingly leaving a sharp edge on the die which would be worn away very quickly by the cutting action. The result would be inaccurate mating of the punch and die and the resulting uneven edges on the notch would have a deleterious effect on the electrical field inside the anode 31. One of the primary values of this type of ion trap cathode ray tube lies in the fact that the electron beam is always acted upon by substantially symmetrical electric fields, and this advantage would be lost if the field were distorted by burrs or misalignment of the electrodes.

The electron gun in Figure 5 is supported by a pair of glass rod supports 114, 116, which lie in the same plane. Each of the electrodes; namely, the control grid 111, the second grid 112, and the anode 113 is supported by two pairs of metal posts which are welded to the respective electrodes and inserted into the glass rods 114 and 116 when these latter two are in a molten state. The posts 117 holding the control grid 111, the posts 118 holding the second grid 112 and the rear set of posts 119 on the anode 113 are welded substantially perpendicularly thereto and consequently present no unusual difficulties. On the other hand the forward posts 121 are welded substantially parallel to the posts 119 and so must be welded at an acute angle to the cylindrical wall of the fore part 131 of the anode 113 as shown in Figure 6.

Figure 7 illustrates a way of making these parts where the fore part 131 of the anode 113 is held by a clamp 122, which forms one contact for the welding device 123. The other contact 124 is clamped to the wire 126. When the wire 126 is pulled down into contact with the portion 131, the weld is formed at the point of contact and the wire 126 is cut off at a predetermined length above the point of contact to form the post 121. The clamp 124 is then moved up the wire 126 and the machine is ready for a new half section 131 to be moved into place.

When the wire is forced into contact with the cylindrical wall of the half section 131, it is likely to skid down the slope, and to prevent this the wall of the half cylinder 131 may be deformed to a slight dent or level spot in the area sur-

rounding the point of contact to form the area 132. The deformation may be of any desired form, but must not be great enough to distort the electrical field.

Although I have described this invention in relation to specific embodiments, they are to be interpreted as illustrations and it is understood the structure may be varied without departing from the spirit or scope of the invention.

10 What is claimed is:

1. A bent cylindrical anode for a cathode ray tube, said anode comprising two sections which are substantially mirror images of each other, each of said sections comprising a semi-cylindrical portion having the axis thereof formed of two lines intercepting at an angle, and lying in the plane intercepting said anode to form said sections, substantially planar radial flanges extending along the edges of said semi-cylindrical portions, said flanges on one of said sections abutting matching flanges on the matching section and being joined thereto.

2. A bent, metallic, cylindrical anode for a cathode ray tube, said anode comprising two sections which are substantially mirror images of each other, each of said sections comprising a semi-cylindrical portion having the axis thereof forming an angle, flanges extending from the two longitudinal edges of each of said sections, both of said flanges being substantially co-planar with the flanges of the matching section and being joined thereto, said anode being bent, to form said angle, in the plane of said flanges.

3. A bent, metallic, cylindrical anode for a cathode ray tube, said anode comprising two sections which match each other, each of said sections comprising a semicylindrical portion having its axis bent, to define an angle, in the plane of the longitudinal edges of said semicylindrical sections, flanges extending from the longitudinal edges of each of said sections, said flanges being substantially co-planar with the flanges of one section abutting matching flanges on the other section and being joined thereto, and an indented stiffening rib located transversely of the axes of said cylindrical anode proximal to one end thereof, with a corona shield having a turned back rim and a radially extending rib matching the inner surface of said stiffening rib held thereby.

4. A bent, metallic, cylindrical anode for a cathode ray tube, said anode comprising two sections matching each other, each of said sections comprising a semicylindrical portion having the respective axis thereof bent to define an angle and lying in a plane intercepting said anode to form said sections, flanges extending from the two longitudinal edges of each of said sections, said flanges being substantially co-planar with the flanges of the matching section and being joined thereto, said anode being held by vitreous supports on either side thereof and being secured to said vitreous supports by a plurality of metal posts.

5. The anode structure in accordance with claim 4 in which each said section has a plurality of substantially flat portions in the curved side thereof, each of said posts being joined to said anode with respective ends of said posts abutting said flat portions.

6. The anode structure in accordance with claim 4 in which said posts are joined to said vitreous supports by molding one end in the side thereof to extend radially therefrom.

7. The anode structure in accordance with claim 4 in which said vitreous supports lie in a

plane normal to the plane intercepting said anode to form said sections.
